UNITED STATES PATENT OFFICE.

ALBERT FLANDERS WOOD, OF DETROIT, MICHIGAN.

DESIGN FOR A BOX.

SPECIFICATION forming part of Design No. 34,618, dated June 4, 1901.

Application filed March 15, 1901. Serial No. 51,385. Term of patent 14 years.

To all whom it may concern:

Be it known that I, ALBERT FLANDERS WOOD, a citizen of the United States, residing at the city of Detroit, in the county of Wayne and State of Michigan, have invented and produced a new and original Design for Boxes, of which the following is a specification, reference being had to the accompanying drawing, forming a part thereof.

10 This invention relates to an original design for boxes.

The figure of the drawing is a perspective view of a box embodying the design.

As shown in the drawing, the design consists of a box A, provided with a scalloped construction of top B, the outer rim C of the same

being formed of rounded projections a. The center of the top is flat and plain and occupies a plane somewhat below that of the upper surface of the rim C.

20

The essential feature of the design is the box provided with a top having a projecting rim the edge of which is scalloped.

What is claimed is—

25 The design for a box, substantially as herein shown and described.

In testimony whereof I affix my signature in presence of two witnesses.

ALBERT FLANDERS WOOD.

Witnesses:

SHELDON A. WOOD,
MINNIE BEAM.
